United States Patent Office.

JOHN OESTERLING, OF WHEELING, WEST VIRGINIA.

Design No. 4,263, dated July 26, 1870.

DESIGN FOR GLASS-WARE.

The Schedule referred to in these Letters Patent and making part of the same

To all whom it may concern:

Be it known that I, JOHN OESTERLING, of Wheeling, in the county of Ohio and State of West Virginia, have invented a new and original Design for Pressed Glass-Ware; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made,

the said design being a continuous rose-wreath for pressed glass-ware.

Having thus described my invention, I claim as new and desire to secure by Letters Patent—

The design for pressed glass-ware, as shown.

JOHN OESTERLING.
